BILL AND COIN CHANGER

Melvin H. Boldt, Glenview, Ill., assignor to Rowe International, Inc., Whippany, N.J., a corporation of Delaware

Filed Sept. 4, 1969, Ser. No. 18,997

Term of patent 14 years

Int. Cl. D20—99

U.S. Cl. D52—4

Fig 1

FIG. 2

FIG. 1 is a perspective view of a bill and coin changer showing my new design;

FIG. 2 is a left side elevational view, the right side elevational view being a mirror image thereof; and

FIG. 3 is a top plan view thereof.

I claim:

The ornamental design for a bill and coin changer, substantially as shown and described.
